UNITED STATES PATENT OFFICE

HARVEY H. HALLER, OF LOS ANGELES, CALIFORNIA, ASSIGNOR TO THE WEHR MOTOR COMPANY, OF LOS ANGELES, CALIFORNIA, A CORPORATION OF CALIFORNIA

VALVE CONSTRUCTION

Application filed July 19, 1930. Serial No. 469,179.

My invention relates to valve constructions, and more particularly to those for internal combustion engines wherein means are provided for effectively compensating for any 5 variations in temperature and wear conditions, means being also provided whereby an effective lubrication may be had under all conditions of operation of said engine.

It accordingly is an object of my invention 10 to provide a novel form of valve construction adapted for special use in connection with internal combustion engines, said construction comprising a set of shoes which are not only adapted to be moved simultaneously but 15 relatively to each other, one of said shoes being provided with means in the shape of slots or cut-out portions which render said shoe more elastic, and the shoe assembly provided with a set of grooves and passages whereby 20 the contacting surfaces as well as the upper and lower surfaces of said assembly may be effectively lubricated.

The above, and further objects and advantages of my invention, as will hereinafter 25 more fully appear, I attain by the construction described in the specification and illustrated in its preferred form on the drawing, forming a part of my application.

Reference is had to the accompanying 30 drawing, in which similar reference characters denote similar parts. In the drawing,

Fig. 1 is a fragmentary cross-sectional view 35 of an internal combustion engine provided with my invention,

Fig. 2 is an enlarged perspective view of the upper compensating shoe,

Fig. 3 is a cross-sectional view, taken on the line 3—3, Fig. 2,

Fig. 4 is an enlarged cross-sectional view 40 taken on the line 4—4, Fig. 3,

Fig. 5 is an enlarged perspective view of the lower shoe,

Fig. 6 is a cross-sectional view, taken on the line 6—6, Fig. 5,

Fig. 7 is a bottom plan view of Fig. 6,

Fig. 8 is a longitudinal sectional view taken through the vertical center line of Fig. 1, but on a smaller scale, and

Fig. 9 is a fragmentary cross-sectional 50 view on a somewhat enlarged scale, illus-

trating more particularly the cut-out portions of the valve casing.

Describing my invention more in detail, in its broader aspects said invention comprises 55 a set of coacting, complementary shoes for relative and simultaneous movement, one of said shoes being provided with slots or cut-away portions to render same more elastic, the assembly being also provided with a set of lubricating passages and grooves in fluid 60 connection, whereby the upper and lower surfaces of the assembly, as well as the engaging surfaces will at all times be effectively lubricated.

More specifically, my invention comprises 65 an internal combustion engine 2, provided with the usual cooling channels, and a valve casing or casting 4 which has associated therewith a cylinder port 6, adapted to be controlled by a rotary valve 8, rotating in 70 the direction of the arrow on Fig. 1, which valve has a set of passages 10 adapted selectively to bring the inlet port 12 in connection with the cylinder port 6 and the exhaust port 14 in connection with said cylinder port. 75

The valve casing 4 has a cover 16, detachably associated with said casing by means of screw bolts 18, and has its inner surface tapered as shown in Fig. 1, for a purpose 80 presently to be described.

Said valve casing is also provided with an adjustable bolt and spring assembly 20, the bolt of which is adapted to engage with a depression 22 in one end of the lower shoe 85 24 of the temperature and wear compensating assembly.

The lower shoe 24 of said assembly is double concave in construction and is provided with lubricating grooves and passages 90 to provide for effective lubrication of the valve 8, said shoe having a preferably central lubricating passage 26, connected with a diagonal passage 28, which diagonal passage connects with a cross-groove 30, on one surface of said shoe, and on the other with a longitudinal lubricating groove 32.

The upper shoe of said assembly is designated by the reference numeral 34, and has a thorough lubricating passage 36 adapted at 100 all times to be in fluid connection with the

passage 38 in the cover 16, to which may be connected a source of lubricant supply.

The upper surface of the shoe 34 has a cross lubricating groove 40 in fluid connection with the passages 36, and a lower lubricating groove 42, also in fluid connection with said passage so that the upper and lower surfaces of said shoe are continually lubricated.

10 The upper surface of the shoe 34 is so constructed that it will adapt itself to the taper of the inner wall of the cover 16, so there will be a continual wedging action of the shoe assembly under pressure of the spring assembly 20, sufficient clearance in the valve casing 4 being provided to that end, which in practice is quite slight. See Fig. 1.

15 It has been found in practice that there are inaccuracies due to faulty machining, so that the shoes are not all uniform. To compensate for said inaccuracies the shoe 34 may be provided with slots or cut-out portions 44, extending preferably from each end across the entire sides of said shoe, which slots or 20 cut-out portions render said shoe more elastic so that an accurate fit is at all times maintained between the shoes 24 and 34.

25 The valve casing 4 is also provided with a cut-out portion 46 (Fig. 1) in fluid connection with the groove 30 of the shoe 24, whereby the entire periphery of the valve 8 will be lubricated.

30 As the valve 8 is rotated in the direction of the arrow shown in Fig. 1, the compensating shoe assembly has a wedging action in respect thereto, being urged to said valve by reason of the spring assembly 20 along the inclined inner wall of the cover 16, the upper shoe 34, also having a relative arcuate movement with respect to the lower shoe 24, thus 35 effectively compensating for all varying conditions of temperature and wear, the lubricating passages and grooves at all times effectively lubricating all engaging and rubbing surfaces.

40 In accordance with the provisions of the patent statutes, I have described the principle of operation of my invention together with the apparatus which I now consider to represent the best embodiment thereof; but I desire to have it understood that the apparatus is only illustrative, and that the invention 45 can be carried out by other means.

45 I claim as my invention:

50 1. In a valve construction, in combination with a double-concave shoe, a plano-convex shoe provided with cut-out portions in the sides thereof for rendering said plano-convex shoe more elastic.

55 2. An upper compensating shoe adapted for special use in connection with valve constructions, said upper shoe in combination with a lower shoe having an upper plane surface 60 and a lower convex surface, there being a set

of transverse slots associated with said shoe for rendering same more elastic.

3. An upper compensating shoe in combination with a lower shoe having an upper plane surface and a lower convex surface, said upper shoe being provided at its sides and ends with a set of slots to render said shoe more elastic. 70

4. An upper compensating shoe provided with a plane surface and a convex surface, 75 in combination with a lower shoe, said upper shoe being provided with a lubricating passage therethrough in fluid connection with lubricating grooves in said plane surface and said convex surface, said shoe being also provided with a set of slots to render said shoe more elastic. 80

5. A double concave compensating shoe adapted for use in connection with another shoe in valve constructions, said double-concave shoe being provided with a lubricating passage leading from a groove in one concaved surface to a diagonal passage in said shoe and connecting with a lubricating groove in the other of said concaved surfaces. 90

6. A temperature and wear compensating means for internal combustion engines comprising a plano-convex upper shoe provided with cut-out portions in the sides thereof for rendering said shoe more elastic, and a double-concave lower shoe in juxtaposition with said upper shoe and adapted both for relative and simultaneous movement therewith, said shoes having sets of lubricating grooves in the surfaces thereof and connected by lubricating passages. 95

7. A double concave and convex compensating shoe assembly for the rotary valves of internal combustion engines comprising a pair of simultaneously and relatively movable members, each provided with upper and lower grooves and through passages in fluid connection with each other connected to a source of lubricant whereby the engaging and rubbing surfaces may be continually lubricated. 105

8. In an internal combustion engine, a valve casing, a cover for said casing having an inner inclined surface, a rotary valve in said casing, and a temperature and wear compensating assembly adapted to have a wedging action between said inner surface and said valve, said assembly comprising upper and lower members, said upper member being provided with upper and lower grooves connected by a through passage and connected to a source of lubricant supply, said lower member being provided with upper and lower grooves in fluid connection with a diagonal through passage whereby said surface, said valve and the engaging surfaces of said assembly are continually lubricated. 115

9. A double concave and convex temperature and wear compensating shoe assembly of two parts, each part being provided with upper and lower cut-away portions and 120

125

130

through passages connected to a source of lubricant whereby all rubbing and engaging surfaces of said assembly will be continually lubricated.

5 In testimony whereof I have signed my name to this specification.

HARVEY H. HALLER.
